UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

REVERSIBLE LOCK.

Application filed May 3, 1922. Serial No. 558,178.

To all whom it may concern:

Be it known that I, ERNEST L. TEICH, a citizen of the United States, residing at New Britain, county of Hartford, State of Connecticut, have invented a certain new and useful Improvement in Reversible Locks, of which the following is a full, clear, and exact description.

The present invention relates to locks, and more particularly to locks for double doors of the type having rabbeted edges that are arranged to engage when the doors are closed, doors of this type being usually used as closures in what are known as French windows.

An object of the invention is to provide a lock of this character which is capable of being applied to either right or left hand French doors.

Another object of the invention is to provide striker and face plates for locks for French doors which are capable of being applied to either right or left hand doors.

The several features of the invention whereby the above mentioned and other objects of the invention may be attained will be clearly understood from the following description and accompanying drawings, in which:—

30 Fig. 1 is a front view of a portion of a pair of French doors with a lock applied to a right hand door embodying the features of the invention in their preferred form;

35 Fig. 2 is an inner or front edge view of a portion of one of the doors showing particularly the face plate of the lock;

Fig. 3 is a similar view of the other door showing particularly the striker plate of the lock;

40 Fig. 4 is a view similar to Fig. 1 but showing the lock applied to a left hand French door;

Fig. 5 is an inner or front edge view of one of the doors shown in Fig. 4 showing particularly the striker plate of the lock;

45 Fig. 6 is a similar view of the other door showing particularly the face plate of the lock;

Figs. 7 and 8 are sectional views taken on the lines 7—7 and 8—8 of Figs. 1 and 4 respectively; and

Figs. 9 and 10 are detailed perspective views of component parts of the striker plate and face plate, respectively, of the lock.

55 The doors illustrated in the drawings are

of the usual French type consisting of two opposed swinging doors 2 and 4 having their inner or front edges provided with rabbets 6 forming opposed flanges 8 that are arranged to engage when the doors are closed so as to form a rabbet joint, the door 2 carrying the lock and the rabbeting in the doors illustrated in Fig. 1 of the drawings being such as to provide right hand doors, and the rabbeting of the doors illustrated in Fig. 4 being such as to provide left hand doors. The lock which is mounted in the usual mortise or recess 10 of the door 2 is provided with a case 12, a cover 14 for the case, knobs 16, and a knob operated latch bolt 18 which is so arranged as to be capable of being reversed in position. The forward end of the lock case projects a distance from the pocket 10 and the flange 8 of the door 4 is cut away at 19 to clear the projecting portion of the lock case when the doors are closed. The lock is further provided with a face plate 20 which is secured by screws 22 to the front of the lock case 12 so that it can be easily removed and reversed. The lock is secured by screws 23 to the front of the flange 8 of the door 2, the flange 8 being provided with a depression or recess for receiving the face plate so as to cause the face plate when attached to be flush with the inner or front face of the door flange 8. The face plate is provided with the usual latch receiving aperture 23 and lock bolt receiving aperture 24. The face plate projects slightly beyond the sides of the lock case and the end portions of the plate project a distance beyond the ends of the lock case and are cut away at 21 to cause the inner edges of these projecting portions to be flush with the side of the door flange 8.

In the illustrated construction the face plate is provided with a flange 25 made separate from the plate and secured by a screw 26 to the side of the projecting portion of the lock case 12 and if desired by screws 26' to the side of the door flange 8. The flange 25 is substantially of the shape of the inner edge of the face plate and is so arranged as to be substantially flush with said inner edge, the door flange 8 being suitably recessed to receive the end portions of the flange 25.

The lock is further provided with a striker plate 27 which is secured by screws 28 at its ends to the front wall 6 of the

rabbit of the door 4, the plate being substantially of the same length as the face plate and having its inner edge shaped to fit the wall of the cut away portion 19 of the door flange. The front wall of the rabbit is suitably recessed to cause the striker plate to be flush therewith. The striker plate is provided with the usual latch bolt receiving aperture 30 and the lock bolt receiving aperture 32.

In the illustrated construction the striker plate is provided with a flange 34 made separate therefrom and shaped to fit the wall of the cut away portion 19 of the door flange with its inner longitudinal edge abutting the face of the striker plate. The flange 34 is secured at its ends to the door flange 8 by screws 36.

It has been customary heretofore to make the flanges of the striker and face plates integral therewith, with the result that it has been necessary to manufacture striker and face plates of two different constructions, one for right hand and the other for left hand French doors. By making the flanges separate from the plates, however, as above described, it will be apparent that the flanges may be reversed in respect to the sides of their respective plates so as to enable a single lock or striker plate to be used on either right or left hand doors, so that it is necessary to keep on hand for installation, striker and face plates of but one construction. The lock is provided with a reversible latch bolt of ordinary construction, and the complete lock, including the striker and face plates, may by reversing the plates and transferring the flanges, as shown, be used on either right or left hand doors.

As will be evident to those skilled in the art, my invention permits of various modifications without departing from the spirit thereof or the scope of the appended claims.

45 What I claim is:

1. A lock for double doors of the type having rabbeted edges forming flanges that are arranged to engage when the doors are closed having, in combination, a lock case and a reversible latch bolt mounted in one of the doors, a reversible face plate for the lock adapted to be applied to the front face of the flange of said door, a reversible striker plate adapted to be applied to the front wall of the rabbet of the other door, and flanges for both of said plates adapted to be applied to the inner sides of the flanges

of the doors and to either side of the plates, respectively, to enable the lock to be used on either right or left hand doors.

2. A lock for double doors of the type having rabbeted edges forming flanges that are arranged to engage when the doors are closed having, in combination, a lock case and a reversible latch bolt mounted in one of the doors, a face plate adapted to be applied to the front face of the flange of said door, a striker plate adapted to be applied to the front wall of the rabbet of the other door one of said plates being reversible and a flange for said reversible plate adapted to be applied to the inner side of the flange of the door to which said plate is applied and to be arranged at either side of the plate to enable the plate and its flange to be used on either right or left hand doors.

3. A lock for a door having a rabbeted front edge forming a flange having, in combination, a reversible latch bolt, a reversible face plate for the lock adapted to be applied to the front face of the door flange, and a flange for the plate adapted to be applied to the inner side of the door flange and to either side of the plate.

4. A lock for double doors of the type having rabbeted edges forming flanges that are arranged to engage when the doors are closed having, in combination, a lock case and a reversible latch bolt mounted in one of the doors, a reversible face plate adapted to be applied to the front face of the flange of said door, a reversible striker plate adapted to be applied to the front wall of the rabbet of the other door, one of said plates having its longitudinal edges unsymmetrical, and a flange for said plate adapted to be applied to the inner side of the flange of the door to which said plate is applied and to either side of one of said edges of the plate to enable the plate and its flange to be used on either right or left hand doors.

5. A lock for a door having a rabbeted front edge forming a flange having, in combination, a reversible latch bolt, a reversible face plate for the lock adapted to be applied to the front face of the door flange and having its longitudinal edges unsymmetrical, and a flange for the plate adapted to be applied to the inner side of the door flange and to either side of one of said edges of the plate.

ERNEST L. TEICH.
